UNITED STATES PATENT OFFICE.

CHARLES F. McBEE, OF ATHENS, OHIO, ASSIGNOR TO THE McBEE BINDER COMPANY, OF ATHENS, OHIO.

PERFORATING DEVICE.

1,338,457.

Specification of Letters Patent.

Patented Apr. 27, 1920.

Application filed December 30, 1918. Serial No. 269,012.

To all whom it may concern:

Be it known that I, CHARLES F. McBEE, a citizen of the United States, residing at Athens, in the county of Athens, State of Ohio, have invented a certain new and useful Improvement in Perforating Devices, of which the following is a specification.

The object of my invention is to provide a punch or perforating device, adapted to insure registration of the punch shafts with the receiving orifices when the said shafts become slightly displaced and out of line. My device is designed particularly for that class of punches wherein the punch post, or shaft, is of some considerable length, for it is in such constructions that slight displacements are frequent, and result in imperfect and improper operation of the punch or render it completely inoperative.

My invention consists of certain details of construction hereinafter set forth, pointed out in my claims and illustrated in the accompanying drawings, in which Figure 1 shows a front elevation of my device, partially in section, and

Fig. 2 shows a side elevation of the same.

Referring to the accompanying drawings the reference numeral 10 is used to indicate the base of the punch, with vertical tubular posts, 11 and 12, mounted thereon to receive guide shafts, 13 and 14 respectively, designed to be actuated by springs 15 and 16 mounted in the orifices below the said shafts, as shown. The numerals 17 and 18 indicate slots in the said posts to receive lugs 19 and 20 respectively, secured to the guide shafts, thus providing means to limit both the upward and downward movement of the guide shafts in their mountings. The said guide shafts extend downwardly from a plate 21 which is provided with orifices 22 to receive punch shafts 23 extending upwardly from, and secured to, the base 10. These said orifices are beveled at their lower ends, at 24, as clearly shown. The numeral 25 indicates a handle on the plate 21.

In a punch requiring long punch shafts it frequently occurs that the shafts, by reason of their length, get slightly out of reg-

ister with their receiving orifices, and it is 50 practically impossible to repair same. By reason of slightly beveling, outwardly, the receiving orifices 22 if the punch shaft 23 should be slightly out of true it will still be received by the beveled surface and directed 55 through the orifice and the papers be perforated. By practical usage it has been demonstrated that this construction is very satisfactory and positively accomplishes the objects sought.

Having thus described my invention what I claim and desire to secure by Letters Patent of the United States, is:

1. A punch comprising a base provided with perforating shafts near its outer end, a 65 plate provided with perforating shafts, beveled orifices near its outer end adapted to receive said perforating shafts, said plate having guide shafts adjacent the inner side of the punch shafts, there being orifices in 70 the base provided with springs adapted to actuate the said guide shafts, said base being provided with posts to receive said guide shafts.

2. A punch comprising a base having 75 elongated perforating shafts; a receiving member for said shafts, provided with receiving orifices the longer portion of their inner surfaces being in a vertical line the lower portions thereof being beveled outwardly, guide posts located on the inner side of the perforating shafts, there being orifices within said base and means in said base adapted to actuate said guide shafts, substantially as shown and described.

3. A punch comprising a base, provided with punch shafts near its outer end, a plate provided with orifices near its outer end adapted to receive said punch shafts, said plate having guide shafts adjacent the inner side of the punch shafts, there being orifices in the base provided with springs adapted to actuate the said guide shafts, said base being provided with tubular posts to receive said guide shafts.

4. A punch comprising a base, provided with punch shafts near its outer end, a plate provided with orifices beveled outwardly at

their lower ends, adapted to receive said punch shafts, said plate having guide shafts adjacent the inner side of the punch shafts, there being orifices in the base provided 5 with springs adapted to actuate the said guide shafts, said base being provided with tubular posts to receive said guide shafts, and a handle attached to said plate, and

means to limit both the upward and downward movement of the guide shafts.

In testimony whereof I have signed the foregoing specification. 10

CHARLES F. McBEE.
